Application May 9, 1940, Serial No. 334,123

36 Claims. (Cl. 315—129)

The present invention relates to stroboscopes. In Letters Patent 2,185,189, granted January 2, 1940, and applications, Serial Nos. 129,837 and 129,838, filed March 9, 1937, which matured on May 21, 1940, into Letters Patent 2,201,166 and 2,201,167, of the former of which the present application is a continuation-in-part, there is disclosed a gaseous-discharge cold-cathode tube particularly adapted for uses requiring large peak currents, with relatively small average currents.

As that tube is capable of providing very brief and intense flashes of light, such as are necessary for stroboscopic observation, an object of the present invention is to provide a new and improved stroboscope in which the said gaseous-discharge device constitutes the lamp.

Still another object of the invention is to provide a novel method of and means for calibrating the frequency scale of the above stroboscope.

Other objects will be explained hereinafter and will be particularly pointed out in the appended claims.

For a consideration of what I believe to be novel and my invention, attention is directed to the accompanying description and the claims appended thereto.

In the accompanying drawings, Fig. 1 is a circuit diagram illustrating a preferred complete stroboscope circuit embodying the invention, with a conventional power supply to furnish direct current from alternating-current mains, a separate oscillator for driving the stroboscopic lamp so as to cause the lamp to flash at the desired frequency, means for calibrating the oscillator, means for operating the lamp so as to cause it to flash at the frequency of the alternating-current supply voltage from the line, and a contactor device for controlling the flashing rate; Fig. 2 is an enlarged view of a plurality of scales; and Fig. 3 is a view similar to Fig. 1 of a modification illustrating a single knob for controlling all the switches.

The tube 1 employed in the circuits embodying the present invention may be of the cold-cathode gaseous-discharge type illustrated and described in the said Letters Patent 2,185,189, 2,201,166 and 2,201,167. It may comprise an evacuated glass envelope filled with a suitable gas, such as neon, or any of the other noble gases, such as argon or helium. The pressure of the gas in the tube may vary, the usual pressure being from one to two centimeters. The tube contains several electrodes, namely, a solid cathode 2, an anode or plate 5, and one or more grids, inner and outer grids being shown at 3 and 4 between the anode 5 and the cathode 2. The grid 3 is at zero potential with respect to the cathode 2 and the grid 4 is positive with respect to the grid 3. The source of the electrons is a bright cathode spot on the surface of the cathode. Either grid may be used as the control electrode, depending upon the polarity and the magnitude of the control voltage. Further details may be obtained by reference to the said Letters Patent.

As explained in the said Letters Patent 2,185,189 and 2,201,166, the grid 3 may, in normal use, be placed close to the cathode 2, say, not more than a few millimeters from the cathode, and may be of such shape that the cathode will sputter a thin surface layer or coating of a material of low work-function that does not combine chemically with the gas in the envelope, such as caesium, on the grid surface. A thin surface coating or layer of the caesium or other material of low work-function is thus maintained on the grid 3 during the normal operation of the tube. As explained in the said Letters Patent 2,201,167, however, the grid 3 may, under certain circumstances, be precoated.

The form of the arc stream between the anode and the cathode is a column of small diameter which has high intrinsic brilliance, with substantially all the light emitted from the concentrated arc stream. This discharge is easily distinguished from a glow discharge, which occupies substantially the whole interior of the tube, with a discharge of low intrinsic brilliance, the greatest brilliance being at the surface of the cathode.

In the illustrated stroboscopic circuit, the anode 5 and the cathode 2 of the tube are shown connected across a condenser 11, which is continuously charged, by way of conducting wires 7 and 8, from a suitable direct-current source of, say, 300 to 400 volts, connected through a variable current-limiting impedance 12, which may be a resistor, or a combination of resistance and inductance. The source may be constituted of thermionic or gaseous-discharge rectifiers for producing direct current from alternating current, as illustrated, or any other source of direct current.

In the illustrative circuit, a transformer 18, a double-anode rectifier tube 17 and a condenser 19 form a conventional power supply to give any desired direct-current voltage, say, 300 volts, from the 110-volt alternating current mains.

The discharge condenser 11 is used for high-frequency operation of the stroboscope circuit;

for low-frequency operation, a condenser 13 is connected in parallel with the condenser 11 by means of a switch 66.

As explained more fully in the said Letters Patent, in the operation of the circuit, the condenser 11 starts to become charged from the direct-current source through the impedance 12, the tube being non-conductive. When the voltage across the condenser 11 reaches the required value, say, 110 volts, however, the voltage between the grid 4 and the cathode 2 exceeds the breakdown value and the tube becomes conducting. The current passes between the anode and the cathode continually but interruptedly to set up continually discharges of arc characteristic between the cathode and the anode. It is of amperage sufficiently high to produce a potential gradient on a relatively small area only of the cathode high enough to extract electrons from the cathode while the cathode remains "cold," at low average temperature, and to produce a fall of cathode potential lower than that occurring in a glow discharge. The average value of the said current is nevertheless relatively low. If a pill constituted of caesium chloride and aluminum, for example, be employed as the cathode, the action of the cathode spot causes the caesium chloride to break down, aluminum being substituted for the caesium and forming aluminum chloride. The intervals between the discharges are sufficiently large so that the average temperature of the cathode remains low enough to prevent rapid disintegration of the cathode.

Impedances 79 and 80 are shown connected between the cathode 2 and the grid 4, and between the grid 4 and the anode 5, respectively; and an impedance 81 is shown connected between the cathode 2 and the grid 3. The bias is so adjusted on the grid 4 by means of these impedances, which may be resistors, and the supply voltage is so adjusted, that it is possible to have the voltage between the anode 5 and the cathode 2 much greater than the voltage required to cause a glow discharge between the grid 4 and the grid 3, and the tube will thus stay in a non-conducting state when the condenser 11 is fully charged. The lamp circuit comprises the said two discharge condensers 11 and 13, the said current-limiting resistor 12 and the three resistors 81, 80 and 79.

Current is also supplied from the power supply to conductors 100 and 132. The conductor 132 is connected through a resistor 124, to a switch 86, adapted to occupy two positions A and B. The conductor 100 is connected, by a contactor device 87, to a contact member with which the switch 86 is adapted to contact in position B. The circuits of the hereinafter-described multivibrator are open when the switch 86 occupies the position B. The switch 86 is connected by a conductor 58, through a condenser 83, to the grid 3. The switch 86 is connected also to the source of alternating current, by way of a conductor 20, and through a resistor 84, by a switch 85. The contactor 87 may be periodically opened and closed in any desired manner; this is not shown in order to simplify the drawings.

With the switch 86 in position B, and the switch 85 open, the lamp 1 can be triggered at the desired instant by means of the contactor device 87, which causes a momentary surge through the condenser 83. When the contactor device 87 closes, therefore, the grid 3 is given a negative voltage pulse equal to the voltage existing be-

tween the conductors 100 and 132. The condenser 83 then discharges through the resistor 81 and the grid 3 to the cathode 2, allowing the voltage of the grid 3 to return to zero. The discharge circuit extends from one side of the condenser 83, through the resistor 81 and the grid 3 and the cathode 2, in parallel, by way of the conductors 8, 65 and 100, and through the switches 87 and 86, the latter in the position B, to the other side of the condenser 83. Once the contactor 87 becomes closed, it may remain closed without the stroboscope flashing on again when the condensers 11 and 13 build up their voltages. The operation is independent of the length of time that the contactor 87 remains closed, the complete function being performed at the moment it first becomes closed. The contactor 87, therefore, gives only one impulse of voltage at each closing, and the length of time the contactor 87 remains closed does not affect the operation of the tube.

The voltage applied between the grids 3 and 4 should be sufficient to cause an initiating glow discharge between the grid 4 and the coating on the grid 3. The voltage at which this discharge takes place is low and substantially constant, due to the fact that the grids 3 and 4 shield the field between the grids from charges on the glass. To start the glow discharge between the grids may require a voltage of only about a hundred volts and a current of only a fraction of a millampere, so very little power is required.

The use of the controlling oscillator, for impressing its oscillations upon the grid 3, makes it possible to operate the stroboscope without any moving parts.

The illustrated multi-vibrator oscillator is simple and cheap, it possesses constancy of frequency irrespective of variations in applied voltage and an abrupt or saw-tooth wave form, and it has a comparatively high voltage output. The direct-current power supply for the oscillator may be obtained from the power supply for the stroboscope circuit through conductors 64 and 65 and a resistor 67. A filter condenser 68 is provided to remove any slight alternating-current ripple in the direct-current voltage.

The oscillator circuit comprises a pair of electron-discharge vacuum triodes 88 and 89, a pair of anode or plate resistors or other impedances 122 and 124, the grid resistors or other impedances 136 and 138 that are connected to the grids or control electrodes 114 and 116 of the triodes 88 and 89, the grid condensers or electro-storage devices 125, 126, 127 and 128, and the condenser 129. The frequency-control circuit of the said oscillator comprises the variable, calibrating resistors or other impedances 121 and 130 and the potentiometer or other biasing source of energy or other biasing means 118. The set of electrodes of the vacuum triode 89, comprising the filament or cathode 96, the grid or control electrode 114 and the anode 92, and the set of electrodes of the vacuum triode 88, comprising the filament or cathode 98, the grid or control electrode 116 and the anode 94, may be in separate envelopes, or in a single envelope. It is usually more convenient to combine the two in a single tube. The voltage from the voltage source is applied to the oscillator by way of the conductors 100 and 132, between which the oscillator is connected. The calibrating resistor 121 is connected between resistor 67 and conductor 132. The second calibrating resistor 130 is connected, in series with the potentiometer 118 to the conductor 100. The

potentiometer 118 is thus connected between the calibrating resistors 121 and 130.

The cathodes of the oscillator tubes 88 and 89 are connected to the conductor 100. The anodes of the oscillator tubes are connected to the conductor 132 and the resistor 121 through the resistors 122 and 124. The pair of resistances 122 and 124 thus connect the anodes 92 and 94, respectively, to the upper end of the potentiometer 118, which is positive with respect to the cathodes 96 and 98 by reason of the fact that it is connected by the conductor 64, through the resistor 67, to that terminal of the rectifier 71 that is positive with respect to their cathodes. The resistors 122 and 124, therefore, maintain the anodes 92 and 94 positive with respect to the cathodes. The switch 86 is connected, in position A, to the anode 94 of the triode 88. The anodes 92 and 94 are thus connected to one side of the source of voltage by the conductor 132, through the resistances 122 and 124. The cathodes 96 and 98 of these respective triodes are connected to the other side of the voltage source by the conductor 100. The slider 134 of the potentiometer 118 is connected to the two resistors or other impedances 136 and 138 by a conductor 133.

The input circuit of the triode 89 may be traced from the filament 96, by way of the conductor 100, through the calibrating resistor 130, the lower portion of the potentiometer 118, and the adjustable arm 134, and by way of the conductor 133, through the resistor 136, to the grid 114. The input circuit of the triode 88 may similarly be traced from the filament 98, by way of the conductor 100, through the calibrating resistor 130, the lower portion of the potentiometer 118, and the adjustable arm 134, and by way of the conductor 133, through the resistor 138, to the grid 116. One of the ends of each of the respective resistances 136 and 138 is thus connected to one of the respective control electrodes 114 and 116 of the respective tubes 89 and 88. Their other ends are connected to a potential positive with respect to the cathodes 96 and 98, by way of the conductor 133, to the adjustable arm 134 of the potentiometer 118. The said other ends of the resistors 136 and 138 are thus maintained positive with respect to the cathodes 96 and 98. The output circuit of the triode 89 may be traced from the filament 96, by way of the conductor 100, through the calibrating resistor 130, the potentiometer 118, and the calibrating resistor 121 and, by way of the conductor 132, through the resistor 122, to the anode 92. The output circuit of the triode 88 may similarly be traced from the filament 98, by way of the conductor 100, through the calibrating resistor 130, the potentiometer 118 and the calibrating resistor 121 and, by way of the conductor 132, through the resistor 124, to the anode 94. The condenser 125 is connected between the grid 116 of the electron-discharge device 88 and the anode 92 of the electron-discharge device 89, and the condenser 126 may be connected in parallel therewith. The condenser 127 is similarly connected between the grid 114 of the electron-discharge device 89 and the anode 94 of the electron-discharge device 88, and the condenser 128 may be connected in parallel therewith.

With the switch 86 in the position A, the output of the oscillator, taken from the plate of one of the triodes, is connected to the stroboscopic lamp 1 through the coupling condenser 83 and the conductor 58.

The principles of operation of the oscillator and

its production of a saw-tooth wave form are well understood in the art and hence will not be gone into here. In the usual oscillator, the conductor 133, joining the ends of the grid resistors 136 and 138, is connected to the cathode circuit of the triodes, represented by the conductor 100. The frequency of the oscillator is then varied by varying the resistors 136 and 138. Since the resistors 136 and 138 are of considerable magnitude (say 1 megohm), they are not conveniently procurable in the variable form and, furthermore, varying these resistors gives a non-linear frequency scale of the exponential-type.

According to the invention illustrated and described herein and in Letters Patent 2,302,690, issued November 24, 1942, the frequency of the multivibrator is controlled linearly by adjusting the slider 134 back and forth on the potentiometer 118 to vary the positive bias on the grids of the triodes 88 and 89 in a linear fashion. This yields not only a linear frequency scale, but also a wide frequency range—as much as six to one. The potentiometer 118 is calibrated in flashes per minute of the stroboscope lamp, as herein-after more fully described, with the aid of a vibrating reed 140 and the calibrating resistors 121 and 130. It has a direct-reading scale of frequency against resistor setting, instead of an exponential scale, as formerly obtained. A somewhat greater frequency range occurs, moreover, with reasonable values of resistance in the potentiometer 118.

The potentiometer 118 is provided with two linearly calibrated or uniformly divided scales 152 and 154, with a four-to-one factor between them. The frequency of the oscillator is shifted by this factor by means of the condensers 126 and 128. Connecting these condensers in the circuit by means of their accompanying respective switches 156 and 158 reduces the frequency of the oscillator and shifts the whole frequency scale in linear fashion, the amount of the shift depending on the values of the condensers. The stroboscope may have a flashing range extending to over 15,000 flashes per minute.

To insure an absolutely linear scale, it is important that the time constant of the resistor 122 with condenser 125, and the time constant of resistor 124 with condenser 127, be appreciably less than the shortest interval between oscillations at the high-frequency end of the scale. The condenser 129 may be connected across the conductors 100 and 132, in parallel with the resistors 121 and 130 and the potentiometer 118, to correct a slight curvature at the lower end of the scale.

There is a tendency for the scale or scales 152 and 154 to have a further slight curvature in the region of operation of the oscillator with the bias voltage on the grids at the lower end, near the zero, of the scale. This may be corrected for by having the minimum value of the resistor 130 not less about ten per cent of the potentiometer 118. The stability of the oscillator, furthermore, is improved when it is operating with some positive bias on the grids.

Though the potentiometer 118 has a uniform variation of frequency with respect to adjustment of the slider 134, it is not possible, under usual conditions, to make the parts with such precision that, say, an adjustment of the slider 134 throughout the length of the scale will correspond to exactly 600 to 3600 flashes per minute, the extreme figures indicated on the low-frequency scale 152. In actual practice, the varia-

tion in frequency per unit adjustment of the slider 134 may be slightly greater or less than that indicated on the scale. The before-mentioned variable resistors 121 and 130, however, serve to adjust the calibration of the frequency scale by matching the oscillator to the scale. The resistor 121 adjusts the frequency of the oscillator at the high end of the scale to correspond to the scale markings, without appreciably affecting the lower end of the scale, and the resistor 130 similarly adjusts the lower end of the scale, without affecting the higher end. Both resistors 121 and 130, at their respective ends of the scale, serve to adjust the rate at which the frequency of the multivibrator changes in response to changes in the applied bias voltage. By means of these resistors it is possible so to calibrate the oscillator as exactly to match the frequency to the linearly calibrated scale provided, regardless of slight variations in the oscillator circuit due to manufacturing errors or aging of the parts.

It is further desirable to check the calibration of the oscillator, not only at a single frequency but throughout the length of the scale. This may be effected in the same way as the original calibration of the oscillator. According to the specific embodiment of the invention that is illustrated and described herein, the checking apparatus comprises the vibrating reed 140, driven by means of a solenoid 142 in exact synchronism with the alternating current of the line. To this end, the solenoid 142 is connected in circuit with a switch 144 and conductors 146 and 148 across the alternating-current supply. At most localities, the frequency of the alternating mains is controlled with sufficient accuracy to enable the vibrating reed 140 to serve as a standard. The reed is placed so that the light from the flashing lamp falls upon it so that, when the flashing rate of the lamp is the same as the frequency of the reed, the reed appears to stand still. When this occurs, the slider 134 of the potentiometer 118 should be at a marked calibrating point. If it is not, it may be brought to the proper point by adjustments of the calibrating resistors 121 and 130. The check is easily and quickly made and serves to compensate for factors that may impair the calibration.

With the reed 140 operating at 7200 vibrations per minute, for example, a stand-still pattern of the reed may be obtained not only at 3600 vibrations, but also at many multiples and fractional sub-multiples of 120 cycles per second, the reed frequency. The scale may thus be readily checked, for example, at 3600, 2400, 1800, 1440, 1080, 900, 800, 720 and 600 vibrations per minute. These may afford many calibration points of the scale. It usually suffices, in actual practice, to effect the check at two points only, say, 3600 and 900 or 600 vibrations per minute. The resistors 121 and 130, as before explained, enable setting of frequency of the oscillator in terms of the 60-cycle reed 140 to correspond to the scale markings at both ends of the scale, without disturbing the linear variation of frequency with adjustment of the slider 134 over the potentiometer 118. The resistors 121 and 130 may be said to serve the function of so tipping the whole frequency scale that the value, say, 3600, checked at one frequency by means of the reed 140 shall correspond to all frequencies throughout the length of the scale. Uniform rate of change of frequency corresponding to the ad-

justment of the slider 134 is thus preserved throughout the length of the scale.

An alternative method of checking the calibration is shown by a glow lamp 150 and a resistor 149, connected in series to the alternating-current supply at one anode of the rectifier 17 and to the anode 5 of the stroboscope lamp. The glow-lamp 150 will indicate the difference in frequency between the frequency of the alternating-current-supply source and the flashing frequency of the stroboscope. When the frequency of the alternating-current supply and the stroboscope are the same and in phase, the glow lamp will be extinguished. When the frequency is slightly different, the glow lamp will go on and off at a rate equal to the difference in frequency. This is the familiar beat method of matching frequencies.

To elaborate further upon the method of calibration, the slider element 134 is first adjusted to a desired reading of the scale, say, the 3600 reading at the high end of the scale. The corresponding adjustment of the potentiometer 118 will not, however, necessarily be such as to cause the multivibrator to oscillate at the desired 3600 frequency. The resistor 121 will therefore be adjusted until the multivibrator does oscillate at the 3600 frequency. The operator will be guided in his adjustment of the resistor 121 by observing the relation between the flashes of the tube 1 and the vibrations of the reed 140 or the flashes of the glow-tube 150. When the flashing frequency of the tube 1 coincides with the frequency of the vibrating reed 140 or the glow-tube 150, the flashing frequency will be matched against the 3600 reading at the high end of the scale.

The slider 134 will then be set to another reading of the scale, say, the 600 or the 900 reading of the low end of the scale. The resistor 130 will now be adjusted to vary the frequency of the oscillations of the multivibrator, until the flashing frequency of the intermittently flashing tube 1 again coincides with the frequency of the known source of frequency, namely, the vibrating reed 140 or the glow-lamp 150. The flashing frequency will now be matched also against the 600 or the 900 reading at the low end of the scale.

The slider 134 may, in this manner, be set to occupy as many different positions with respect to the scale as desired, and the frequency of the multivibrator may be adjusted at each of these settings in the same way. To each predetermined setting of the slider 134, there will be found to correspond a flashing frequency of the tube 1, the value of which may be obtained by adjustment of one or the other of the resistors 121 and 130. It will be found that two such settings are, in practice, all that are needed. Owing to the fact that the resistor 121 effects adjustment at the high end of the scale without affecting the low end of the scale and without disturbing the linearity, and that the resistor 130 effects adjustment at the low end of the scale without affecting the high end of the scale and without disturbing the linearity, once two readings of the scale have been matched, as above described, all the other flashing frequencies will be found to correspond to the respective positions of the slider 134 with respect to the scale.

By closing the switch 85, an alternating-current voltage is applied to the oscillator from the transformer 78 through the resistance 84 and the conductor 20. This causes the oscillator to run at the frequency of the line voltage and in exact

synchronism therewith. This is useful in certain applications of the stroboscope.

Fig. 3 illustrates a complete stroboscope circuit in which all of the switches are operated by a single controlling knob 302. The circuit is similar to that shown in Fig. 2 and performs the same function.

An output jack 200 is provided in the discharge circuit of the condenser 11 so that the discharge surge of the condenser may be used to operate a larger stroboscope.

The switches 303, 304, 305, 306 and 201 are arranged to be operated by an insulating shaft 301 which may be turned by means of the knob 302. With the switch in the position C, the toggle switch 201 is off. With the switch in any of the positions D, E, F, G and H, the toggle switch is on, thus supplying alternating current through the wires 202, 203, 204 and 205 to the primary of the power transformer 78. With the switch in position D, the condensers 126 and 128 are connected into the oscillator circuit by switches 301 and 304 and the oscillator operates on the low scale 152. Switch 305 connects the output of the oscillator from the plate 94 to the grid 3 of the tube 1 by means of conductor 307, condenser 83 and conductor 58. The switch 306 connects the discharge condenser 13 in parallel with the condenser 11. The stroboscope is thus adapted to run on the low scale.

With the switch in position E, condensers 126 and 128 are disconnected, switch 305 connects the oscillator to the grid 3 and condenser 13 is disconnected. The stroboscope is thus adapted to run on the high scale.

With the switch in the position F, some 60-cycle current is supplied to the grid of the oscillator tube 88, from the secondary of the transformer 78, through resistor 84, through switch 303, and by the conductor 309. The switch 304 connects the condenser 128 in parallel with the condenser 127, switch 305 connects the output of the oscillator to the grid of the tube 1, and switch 306 connects the condenser 13 in parallel with the condenser 11. The stroboscope is thus adapted to operate in synchronism with the alternating supply voltage.

With the switch in position G, the switch 305 disconnects the grid 3 from the oscillator and connects it to the contactor element 87. The circuit is then adapted to be operated by means of the contactor 87 as described in connection with Fig. 2. Switch 306 connects the condenser 13 in parallel with condenser 11, making the operation suitable for low frequencies. For high-frequency contactor operation the switch is turned to position H, which disconnects the condenser 13.

Connecting all the switches to a single control knob greatly simplifies the operation of the stroboscope and makes it a more practical and useful instrument.

In Fig. 3, calibration is effected by means of the resistors 110 and 130.

The light produced by this stroboscope, obtained from a 115-volt, 60-cycle alternating-current source, is sufficient to permit good stroboscopic observation of mechanisms, particularly when the light is concentrated by means of a parabolic reflector. Because of the calibrated frequency scale, the stroboscope is particularly useful in measuring the speed of rotating or vibrating mechanisms.

Modifications will occur to persons skilled in the art, and all such are considered to fall within the scope and spirit of the invention.

What is claimed is:

1. A stroboscope having, in combination, a luminescent-discharge device, means for causing intermittent flashing of the discharge device, a linearly calibrated scale, and means for adjusting the flashing frequency to correspond substantially linearly to the scale throughout substantially the length of the scale.
2. A stroboscope having, in combination, a luminescent-discharge device, an oscillator for causing intermittent flashing of the discharge device, a linearly calibrated scale and means for adjusting the frequency of the oscillator to correspond substantially linearly to the scale throughout substantially the length of the scale, thereby to effect linear calibration of the flashing frequency.
3. A stroboscope having, in combination, a luminescent-discharge device comprising an anode and a cathode of a material that will break down under the action of a cathode spot and form a surface coating thereon of a material of low work-function, a condenser, a charging circuit for connecting the condenser to a source of energy, means for periodically discharging the condenser through the discharge device to subject the cathode and the anode to energy sufficient in character and amount to form cathode spots on the cathode but without supplying sufficient heat to the cathode to cause destruction of the cathode by heat, thereby to cause intermittent flashing of the discharge device, a linearly calibrated scale, and means for adjusting the flashing frequency to correspond substantially linearly to the scale throughout substantially the length of the scale.
4. A stroboscope having, in combination, a luminescent-discharge device comprising an envelope containing gas and having therein electrodes comprising an anode, a solid cold cathode and a control electrode, a condenser, means connecting the condenser to the anode and the cathode, a source of energy, means for charging the condenser from the source, an oscillator, means for impressing the oscillations of the oscillator upon the control electrode to cause electrical discharges to be passed from the condenser periodically between the cathode and the anode through the gas in the envelope to cause intermittent flashing of the discharge device, a linearly calibrated scale, and means for adjusting the frequency of the oscillator to correspond substantially linearly to the scale throughout substantially the length of the scale, thereby to effect linear calibration of the flashing frequency.
5. A stroboscope having, in combination, a luminescent-discharge device comprising an envelope containing gas and having electrodes comprising an anode, a solid cold cathode and a control electrode, the cathode being constituted of a material having a relatively low work-function and that does not combine chemically with the gas in the envelope, means for applying a voltage between the anode and the cathode, an oscillator, means for impressing the oscillations of the oscillator upon the control electrode to cause electrical discharges to be passed periodically between the anode and the cathode through the gas in the envelope to cause intermittent flashing of the discharge device, a linearly calibrated scale, and means for adjusting the frequency of the oscillator to correspond substantially linearly to the scale throughout substantially the length of the scale, thereby to effect linear calibration of the flashing frequency.

6. A stroboscope having, in combination, a luminescent-discharge device comprising an envelope containing gas and having an anode, a cathode, a grid disposed between the anode and the cathode, a grid disposed between the cathode and the first-named grid, an impedance connected between the anode and the first-named grid, an impedance connected between the cathode and the first-named grid, a source of voltage, means connecting the source to the anode and the cathode in parallel to the impedances connected in series, an impedance connected between the cathode and the second-named grid, an oscillator, means for impressing the oscillations of the oscillator upon the second-named grid to cause electrical discharges to be passed periodically between the grids and, therefore, between the cathode and the anode to cause intermittent flashing of the discharge device, a linearly calibrated scale, and means for adjusting the frequency of the oscillator to correspond substantially linearly to the scale throughout substantially the length of the scale, thereby to effect linear calibration of the flashing frequency.

7. A stroboscope having, in combination, a luminescent-discharge device, a multivibrator for causing intermittent flashing of the discharge device, the multivibrator comprising two sets of electrodes, each comprising a cathode, a control electrode and an anode, an input circuit connected between the cathode and the control electrode of each set, an output circuit connected between the cathode and the anode of each set, an impedance connected in the output circuit of one of the sets of electrodes, an impedance connected in the output circuit of the other set of electrodes, two condensers connected, respectively, between the control electrode of each of the sets and the impedance of the other set, and means for energizing the output circuits and for applying an adjustable voltage bias on the control electrodes in substantially linear fashion in order to control the frequency of the multivibrator substantially linearly.

8. A stroboscope having, in combination, a luminescent-discharge device, a multivibrator for causing intermittent flashing of the discharge device, the multivibrator comprising two sets of electrodes, each comprising a cathode, a control electrode and an anode, an input circuit connected between the cathode and the control electrode of each set, an output circuit connected between the cathode and the anode of each set, an impedance connected in the output circuit of one of the sets of electrodes, an impedance connected in the output circuit of the other set of electrodes, two condensers connected, respectively, between the control electrode of each of the sets and the impedance of the other set, means for energizing the output circuits and for applying an adjustable voltage bias on the control electrodes in substantially linear fashion in order to control the frequency of the multivibrator substantially linearly, an impedance, and means for varying the impedance to adjust the rate at which the said frequency changes in response to changes in the applied bias voltage.

9. A stroboscope having, in combination, a luminescent-discharge device, a multivibrator for causing intermittent flashing of the discharge device, the multivibrator comprising two sets of electrodes, each comprising a cathode, a control electrode and an anode, an input circuit connected between the cathode and the control electrode of each set, an output circuit connected be-

tween the cathode and the anode of each set, an impedance connected in the output circuit of one of the sets of electrodes, an impedance connected in the output circuit of the other set of electrodes, two condensers connected, respectively, between the control electrode of each of the sets and the impedance of the other set, a source of energy connected in both output circuits, means for applying an adjustable voltage

10 in substantially linear fashion to the input circuits, and an impedance connected between the source of energy and one of the multivibrator electrodes.

11. A stroboscope having, in combination, a luminescent-discharge device, a multivibrator for causing intermittent flashing of the discharge device, the multivibrator comprising two sets of electrodes, each comprising a cathode, a control electrode and an anode, an input circuit connected between the cathode and the control electrode of each set, an output circuit connected between the cathode and the anode of each set, an impedance connected in the output circuit of one of the sets of electrodes, an impedance connected in the output circuit of the other set of electrodes, means for selectively connecting two pairs of condensers, the condensers of each pair, respectively, between the control electrode of each of the sets and the impedance of the other set, and means for energizing the output circuits and for applying an adjustable voltage bias on the control electrodes in substantially linear fashion in order to control the frequency of the multivibrator substantially linearly.

12. A stroboscope having, in combination, a stroboscopic tube comprising a luminescent-discharge device having an anode and a cathode, a condenser, a source of alternating energy, means for rectifying the energy, means for periodically charging the condenser from the rectified energy, means for connecting the condenser to the anode and the cathode, a multivibrator comprising two sets of electrodes, each comprising a cathode, a control electrode and an anode, an input circuit connected between the cathode and the control electrode of each set, an output circuit connected between the cathode and the anode of each set, an impedance connected in the output circuit of one of the sets of electrodes, an impedance connected in the output circuit of the other set of electrodes, means connected in both output circuits for biasing the control electrodes positively, two condensers connected, respectively, between the control electrodes of each of the sets and the impedance of the other set, and means for comparing the frequency of the multivibrator with that of the source of alternating energy connected in both output circuits comprising a glow lamp connected between the said source and the anode of the luminous-discharge device.

13. A stroboscope comprising a luminescent-discharge device, an oscillator for causing intermittent flashing of said discharge device, means for adjusting the frequency of the said oscillator, a vibrating member energized to vibrate at a predetermined frequency positioned to be illuminated by intermittent flashing of said discharge device, and additional means for adjusting the output frequency of said oscillator to synchronize the intermittent flashing of said discharge device and the vibration of said vibrating member.

14. A stroboscopic tube comprising a luminescent-

discharge device having an anode and a cathode, a condenser, a source of alternating energy, means for rectifying the energy, means for periodically charging the condenser from the rectified energy, means for connecting the condenser to the anode and the cathode, an oscillator for controlling the discharge of the condenser between the anode and the cathode, and means for comparing the frequency of the oscillator with that of the source of alternating energy comprising a glow lamp connected between the said source and the anode.

14. A stroboscope having, in combination, a luminescent-discharge device, a multivibrator for causing intermittent flashing of the discharge device, the multivibrator comprising two sets of electrodes, each comprising a cathode, a control electrode and an anode, an input circuit connected between the cathode and the control electrode of each set, an output circuit connected between the cathode and the anode of each set, means for applying an adjustable voltage in substantially linear fashion to the input circuits, thereby to adjust the flashing frequency substantially linearly, and means for adjusting the rate at which the said frequency changes in response to changes in the applied voltage.

15. A stroboscope having, in combination, a luminescent-discharge device, means for causing intermittent flashing of the discharge device, a linearly calibrated scale, a periodically movable member arranged to be illuminated by intermittent flashing of the discharge device, and means for adjusting the flashing frequency to correspond substantially linearly to the scale and in synchronism with the movements of the periodically movable member.

16. A stroboscope having, in combination, a luminescent-discharge device, means for causing intermittent flashing of the discharge device, a linearly calibrated scale, a vibrating member arranged to be illuminated by intermittent flashing of the discharge device, and means for adjusting the flashing frequency to correspond substantially linearly to the scale and in synchronism with the vibrations of the vibrating member.

17. A stroboscope having, in combination, a luminescent-discharge device, means comprising an oscillator for causing intermittent flashing of the discharge device, a linearly calibrated scale, a vibrating member arranged to be illuminated by intermittent flashing of the discharge device, and means for adjusting the oscillator to adjust the flashing frequency to correspond substantially linearly to the scale and in synchronism with the vibrations of the vibrating member.

18. A stroboscope having, in combination, a scale having an indicator, the scale and the indicator being adapted to be set relative to each other to correspond to predetermined values of the flashing frequency, and means for matching the flashing frequencies of the stroboscope with the scale comprising means for adjusting the flashing frequency to the predetermined values corresponding to the relative settings of the scale and the indicator.

19. A method of matching the flashing frequencies of a stroboscope with a scale having an indicator that comprises setting the scale and the indicator relative to each other to correspond to predetermined values of the flashing frequency, and matching the flashing frequencies of the stroboscope with the scale by adjusting the flashing frequency to the predetermined values cor-

responding to the relative settings of the scale and the indicator.

20. A stroboscope having, in combination, a potentiometer for varying the flashing frequency of the stroboscope comprising a resistor and a slider, a scale having an indicator movable with the slider, the indicator being adapted to be set relative to the scale to predetermined positions corresponding to predetermined values of the flashing frequency, and means for matching the flashing frequencies of the stroboscope with the scale comprising means for adjusting the flashing frequency to the values corresponding to the positions of the slider.

15 21. A stroboscope having, in combination, means adjustable to vary the flashing frequency of the stroboscope, a scale having an indicator adapted to occupy different positions relative to the scale corresponding to different adjustments of the varying means, the scale and the indicator being adapted to be set relative to each other to correspond to predetermined values of the flashing frequency, and means for matching the flashing frequencies of the stroboscope with the scale comprising means for adjusting the flashing frequency to the values corresponding to the relative settings of the scale and the indicator.

22. A stroboscope having, in combination, means adjustable to vary the flashing frequency of the stroboscope, a linearly calibrated scale having an indicator adapted to occupy different positions relative to the scale corresponding to different adjustments of the varying means, the scale and the indicator being adapted to be set relative to each other to correspond to predetermined values of the flashing frequency, and means for matching the flashing frequencies of the stroboscope with the scale comprising two adjustable resistors for adjusting the flashing frequency to the values corresponding to the relative settings of the scale and the indicator, adjustment of one of the resistors controlling the linear correspondence at one end of the scale, and adjustment of the other resistor controlling the linear correspondence at the other end of the scale.

23. A stroboscope having, in combination, a luminescent-discharge device, means for causing intermittent flashing of the discharge device, a scale having an indicator adapted to occupy different positions relative to the scale corresponding to different adjustments of the varying means, the scale and the indicator being adapted to be set relative to each other to correspond to predetermined values of the flashing frequency, and means for matching the frequencies of the stroboscope with the scale comprising means for adjusting the flashing frequency to the values corresponding to the relative settings of the scale and the indicator.

24. A stroboscope having, in combination, an oscillator for varying the flashing frequency of the stroboscope, means adjustable to vary the frequency of the oscillator to vary the flashing frequency, a scale having an indicator adapted to occupy different positions relative to the scale corresponding to different adjustments of the varying means, the scale and the indicator being adapted to be set relative to each other to correspond to predetermined values of the flashing frequency, and means for matching the frequencies of the stroboscope with the scale comprising means for adjusting the frequency of the oscillator to the values corresponding to the relative settings of the scale and the indicator.

75 means for adjusting the frequency of the oscillator to the values corresponding to the relative settings of the scale and the indicator.

lator to adjust the flashing frequency to the values corresponding to the relative settings of the scale and the indicator.

25. A stroboscope having, in combination, a scale having an indicator, the scale and the indicator being adapted to be set relative to each other to correspond to predetermined values of the flashing frequency, a source of known frequency, and means for matching the flashing frequencies of the stroboscope with the scale comprising means for adjusting the flashing frequency into correspondence with the frequency of the source to obtain the values of the flashing frequency corresponding to the relative settings of the scale and the indicator.

26. A method of matching the flashing frequencies of a stroboscope with a scale having an indicator that comprises setting the scale and the indicator relative to each other to correspond to predetermined values of the flashing frequency, and matching the flashing frequencies of the stroboscope with the scale by adjusting the flashing frequency, following upon each setting, into correspondence with the frequency of a source of known frequency to obtain the values of the flashing frequency corresponding to the relative settings of the scale and the indicator.

27. A stroboscope having, in combination, a luminescent-discharge device, an oscillator for causing intermittent flashing of the discharge device, means adjustable to vary the frequency of the oscillator to vary the flashing frequency, a scale having an indicator adapted to occupy different positions relative to the scale corresponding to different adjustments of the varying means, the scale and the indicator being adapted to be set relative to each other to correspond to predetermined values of the flashing frequency, and means for matching the frequencies of the stroboscope with the scale comprising means for adjusting the frequency of the oscillator to adjust the flashing frequency to the values corresponding to the relative settings of the scale and the indicator.

28. A stroboscope having, in combination, a luminescent-discharge device, an oscillator for causing intermittent flashing of the discharge device, the oscillator comprising control-electrode means and a source of energy, means for connecting the source of energy to the control-electrode means, the connecting means being adjustable to adjust the frequency of the oscillator to vary the flashing frequency, a scale having an indicator adapted to occupy different positions relative to the scale corresponding to different adjustments of the connecting means, the scale and the indicator being adapted to be set relative to each other to correspond to predetermined values of the flashing frequency, and means for matching the frequencies of the stroboscope with the scale comprising means for adjusting the frequency of the oscillator to adjust the flashing frequency to the values corresponding to the relative settings of the scale and the indicator.

29. A stroboscope having, in combination, a luminescent-discharge device, a source of alternating energy, means for connecting the discharge device to the source, means for causing intermittent flashing of the discharge device, means adjustable to vary the flashing frequency, a scale having an indicator adapted to occupy different positions relative to the scale corresponding to different adjustments of the varying means, the scale and the indicator being adapted to be set relative to each other to correspond to

predetermined values of the flashing frequency, a glow-lamp connected between the source and the discharge device for indicating the difference in frequency between the frequency of the source and the flashing frequency, and means for matching the flashing frequencies of the stroboscope and the scale comprising means for adjusting the flashing frequency to correspond to the relative settings of the scale and the indicator.

30. A stroboscope having, in combination, a luminescent-discharge device, a source of alternating energy, means for connecting the discharge device to the source, means for causing intermittent flashing of the discharge device, means adjustable to vary the flashing frequency, a scale having an indicator adapted to occupy different positions relative to the scale corresponding to different adjustments of the varying means, the scale and the indicator being adapted to be set relative to each other to correspond to predetermined values of the flashing frequency, a vibratory member positioned to be illuminated by the flashes from the discharge device, means connected to the source for vibrating the vibratory member, and means for matching the flashing frequencies of the stroboscope and the scale comprising means for adjusting the flashing frequency into correspondence with the frequency of vibration of the vibratory member to obtain the values of the flashing frequency corresponding to the relative settings of the scale and the indicator.

31. A stroboscope having, in combination, a luminescent-discharge device, a condenser, a charging circuit for connecting the condenser to a source of energy, means for discharging the condenser through the discharge device to cause intermittent flashing of the discharge device, means adjustable to vary the flashing frequency, a scale having an indicator adapted to occupy different positions relative to the scale corresponding to different adjustments of the varying means, the scale and the indicator being adapted to be set relative to each other to correspond to predetermined values of the flashing frequency, and means for matching the flashing frequencies of the stroboscope with the scale comprising means for adjusting the flashing frequency to the values corresponding to the relative settings of the scale and the indicator.

32. A stroboscope having, in combination, a luminescent-discharge device, an oscillator for causing intermittent flashing of the discharge device, the oscillator having electrodes comprising cathode means, control-electrode means and anode means, an input circuit connected between the cathode means and the control-electrode means, an output circuit connected between the cathode means and the anode means, means for applying an adjustable voltage to the input circuit to vary the flashing frequency, means for adjusting the flashing frequency, a scale having an indicator adapted to occupy different positions relative to the scale corresponding to different adjustments of the voltage-applying means, the scale and the indicator being adapted to be set relative to each other to correspond to predetermined values of the flashing frequency, and means for matching the frequencies of the stroboscope with the scale comprising means for adjusting the frequency of the oscillator to adjust the flashing frequency to the values corresponding to the relative settings of the scale and the indicator.

33. A stroboscope having, in combination, a

luminescent-discharge device, a source of alternating energy, means for connecting the discharge device to the source, means for causing intermittent flashing of the discharge device, means adjustable to vary the flashing frequency, a scale having an indicator adapted to occupy different positions relative to the scale corresponding to different adjustments of the varying means, the scale and the indicator being adapted to be set relative to each other to correspond to predetermined values of the flashing frequency, and means for matching the flashing frequencies of the stroboscope with the scale comprising means for adjusting the flashing frequency into correspondence with the frequencies of the source to obtain the values of the flashing frequency corresponding to the relative settings of the scale and the indicator.

34. A stroboscope having, in combination, a luminescent-discharge device, a multivibrator for causing intermittent flashing of the discharge device, the multivibrator comprising two sets of electrodes, each comprising a cathode, a control electrode and an anode, an input circuit connected between the cathode and the control electrode of each set, an output circuit connected between the cathode and the anode of each set, an impedance connected in the output circuit of one of the sets of electrodes for maintaining the anode of the said one set of electrodes positive with respect to the cathode of the said one set of electrodes, an impedance connected in the output circuit of the other set of electrodes for maintaining the anode of the said other set of electrodes positive with respect to the cathode of the said other set of electrodes, two condensers connected, respectively, between the control electrode of each of the sets and the anode of the other set, means for energizing the output circuits and for applying an adjustable voltage bias on the control electrodes in order to adjust the flashing frequency, and means for adjusting the rate at which the said frequency changes in response to changes in the applied bias voltage.

35. A stroboscope having, in combination, a luminescent-discharge device, a multivibrator for causing intermittent flashing of the discharge device, the multivibrator comprising two sets of electrodes, each comprising a cathode, a control electrode and an anode, an input circuit connected between the cathode and the control electrode of each set, an output circuit connected between the cathode and the anode of each set, an impedance connected in the output circuit of one of the sets of electrodes, an impedance connected in the output circuit of the other set of electrodes, two condensers connected, respectively, between the control electrode of each of the sets and the anode of the other set, and means for energizing the output circuits and for applying an adjustable voltage bias on the control electrodes.

36. A stroboscope having, in combination, an oscillator for varying the flashing frequency of the stroboscope, means adjustable to vary the frequency of the oscillator to vary the flashing frequency, a plurality of scales having a common indicator adapted to occupy different positions with respect to the scales corresponding to different adjustments of the varying means, the scales and the indicator being adapted to be set relative to each other to correspond to predetermined values of the flashing frequency, means for adjusting the frequency of the oscillator to adjust the flashing frequency to the values corresponding to the relative settings of the indicator and one of the scales, whereby the flashing frequencies of the stroboscope will be caused to match with said one scale, and means whereby adjustment of the frequency-adjusting means of the oscillator may be caused to adjust the flashing frequency to the values corresponding to the relative settings of the indicator and the other scale, whereby the flashing frequencies of the stroboscope may be caused to match with said other scale.

KENNETH J. GERMESHAUSEN.

CERTIFICATE OF CORRECTION.

Patent No. 2,331,317.

October 12, 1943.

KENNETH JOSEPH GERMESHAUSEN.

It is hereby certified that error appears in the printed specification of the above numbered patent requiring correction as follows: Page 1, second column, line 18, for "envelope" read --envelope 1--; page 2, second column, line 38, for "constantcy" read--constancy--; line 54, for "electro-storage" read --electron-storage--; line 75, after "potentiometer 118" insert a comma; page 3, second column, line 63, after "less" insert --than--; page 4, second column, line 58, the words "It will be found" should begin a new paragraph; page 5, second column, line 12, claim 2, after "scale" insert a comma; page 6, second column, lines 26 and 27, claim 10, strike out the words and comma "two pairs of condensers," and insert the same after the comma and before "means" in line 26, same claim; and that the said Letters Patent should be read with this correction therein that the same may conform to the record of the case in the Patent Office.

Signed and sealed this 11th day of January, A. D. 1944.

(Seal)
